UNITED STATES PATENT OFFICE.

HOWARD W. WELLES, OF POUGHKEEPSIE, NEW YORK.

WATCH-REGULATOR.

SPECIFICATION forming part of Letters Patent No. 391,101, dated October 16, 1883.

Application filed September 28, 1887. Serial No. 250,017. (No model.)

To all whom it may concern:

Be it known that I, HOWARD W. WELLES, a citizen of the United States, residing at Poughkeepsie, in the county of Dutchess and State of New York, have invented certain new and useful Improvements in Registering-Regulators and Time-Registers for Time-Pieces; and I do hereby declare the following to be a full, clear, and exact description of the invention, such as will enable others skilled in the art to which it appertains to make and use the same.

My invention relates to improvements in registering-regulators and time-registers for time-pieces in which there are independently-movable concentric disks in combination with each other; and the object of my invention or improvements is to provide a new and more effectual means for indicating just how far toward fast or slow the regulator of a time-piece was changed at its last setting, thus enabling any jeweler to place the zero-points of the two disks together at the time of regulating a watch, and so to gage accurately the distance of the new movement of the regulator without the need of any memorandum to refresh his memory at the time of the next variation of the regulator. I attain this object by the device illustrated in the accompanying drawings, in which—

Figure 1 is a plan view of my device as it appears in the interior of a watch. Fig. 2 is an enlarged sectional view of the concentric disks, showing the manner in which they are superimposed in relation to one another.

Similar letters refer to similar parts in both views.

In the drawings, A represents the cock; B, the lower and larger disk, which may be graduated as desired; C, the upper smaller disk; D, the pinion attached to C and cogged. E is the rack of the regulator to be operated by the cogged pinion D. Any other desired method of contact may be used by moving the regulator.

J represents the graduated minute or second time-scale which is old in this connection, and K the double index-hand with both the minute and second end.

The disk B works on A independently of disk C, and friction tight, so that it can be readily set at any point, and the zero-mark on it made to correspond with a line or zero-mark on the concentric disk C.

Suppose the watch is found to have gained six and a half minutes since the last setting. Set the index-hand K, as shown in the drawings, Fig. 1, six and one-half points toward F. Then move the lower disk, B, until its zero-mark corresponds with the middle point between F and S on the concentric disk C. (This central point is approximately shown in Fig. 1.) Then move the latter disk C away from the zero-mark of B toward S, or the slow side, as far as may be thought necessary to correct the error noted in the last twenty-four hours. At the end of the next twenty-four hours the jeweler or wearer of the watch has the whole record before him, and will know almost exactly how much to move the regulator to correct the remaining error. Each subsequent time the regulator is to be moved the disk B should first have its zero-point brought in line with that of disk C to show the next variation of the regulator.

It will be seen that this registering device may be applied to clocks as well as watches by attaching it to one or both sides of the pendulum; nor do I limit myself to two full disks, for I have sometimes used simple index-hands in place of disks, like B, concentric with C and working, like B, friction tight, as a pointer with which to compare the movement of the regulating-disk C. If the variation is only of seconds, the end of the index K (marked s) is to be used.

If it be desired, an additional index-hand may be employed to work on a second scale marked for days, to show the number of days between the several examinations of the watch where they are not made regularly.

What I claim, therefore, and desire to secure by Letters Patent, is—

In a time-piece, a graduated movable disk, B, made concentric with another movable disk or pointer, C, the latter being connected with the regulator-lever, as by pinion and rack, or other convenient method, each of the disks being independent in movement, substantially as and for the purposes described.

In testimony whereof I affix my signature in presence of two witnesses.

HOWARD W. WELLES.
